CENTRIFUGAL PIPE CASTING APPARATUS

Norman F. S. Russell and Frederick C. Langenberg, Edgewater Park, N. J., assignors to United States Pipe and Foundry Company, Burlington, N. J., a corporation of New Jersey

Application November 3, 1934, Serial No. 751,318

16 Claims. (Cl. 22—65)

Our invention relates to centrifugal pipe casting apparatus of the type in which a rotary centrifugal mold is fed with molten metal from a ladle supported at a higher level than the mold and adapted to deliver a stream of molten metal to an inclined chute and a delivery conduit entering the mold and connected with the lower end of the chute and particularly, though not exclusively, our invention relates to and is particularly valuable in connection with that type of centrifugal pipe casting apparatus in which the metal is delivered by the chute to a trough having a delivery spout at its end and through said trough and spout to a relatively reciprocable mold, which mold is rotatable and usually located in a water box or equivalent cooling mechanism, supported on a reciprocable carriage and so actuated as to bring about a progressive delivery of molten metal from one end to the other of the mold. As heretofore constructed, the chutes through which the molten metal passes have been constructed with downwardly inclined channels having converging side walls sufficiently far apart at the point where the metal from the ladle contacts with the chute to receive the stream of metal between them and converging in such manner that the breadth of the channel at the delivery end of the chute corresponds with the breadth of the channel in the trough and it has been found that at times disfigured and defective pipe castings are formed owing to the fact that not infrequently fins or sprays of molten metal are thrown upward and forward from the surface of the metal stream passing through the chute, some of which enter the mold and give rise to defective castings. Again, it has been found that the metal stream delivered to the trough is at times so turbulent as to bring about a splashing of the metal passing through the trough over its edges which again results in more or less defective pipes and, again, it has been found that at times the stream of metal issuing from the spout at the end of the trough is so turbulent as to bring about a splashing of a portion of the delivered metal which, again, may result in the production of more or less defective pipes and it is the object of our invention to so construct and combine the chute with the other parts of the casting apparatus as to prevent or greatly lessen the tendency of the metallic stream passing through the chute to throw out a spray and at the same time to cause the metal to flow through the chute and trough with a minimum of turbulence and so as to greatly lessen the occurrence of splashes from the trough and of

splashing at the delivery spout of the trough. It is a further object of our invention to so modify and reconstruct the structure for supporting the trough in the proper alignment with the mold as to adapt the structure for use with the improved construction of the chute and also to provide an improved structure which will result in a more perfect alignment of the chute with the channel formed in the trough than has heretofore been practical.

It is, of course, well known that a falling stream of a liquid, such as molten cast iron, will fall with a constant acceleration and with a corresponding decrease in cross-sectional area and also that a falling stream of liquid such as molten cast iron of more or less irregular shape will progressively tend to a shape having a circular cross-section. If the stream of liquid, instead of falling vertically, flows through a channel inclined to the vertical, its acceleration is modified by the frictional resistance encountered and by such energy as is lost in changes of direction and, as the guiding channel approaches the horizontal, acceleration may cease to occur so that under some conditions the rate of flow of the liquid may be retarded and, again, the forces acting upon a falling stream of liquid to bring it to a circular section are, of course, mitigated where the liquid flows over an inclined surface. Practical considerations affecting the construction of a centrifugal casting apparatus are such that it is not always practical to locate the ladle with respect to the mold and trough at what might seem from theoretical considerations to be its proper position. The height of the ladle must be such as will bring about a satisfactory rate of flow through the trough and a satisfactory outflow of the molten metal through the delivery spout at the end of the trough. Again, the chute channel must be wide enough to receive the falling stream of molten iron delivered by the ladle at its upper end while at its lower end it should have the breadth of the channel provided in the trough and, as heretofore constructed, the liability of the metal flowing through the chute to throw out sprays of molten metal and to bring about so turbulent a flow as will sometimes cause metal to be thrown over the sides of the trough and to bring about splashing of the metal as it contacts with the mold is, we have found, due to the facts, first, that the longitudinal contour of the chute channel has been such as to effect unduly abrupt changes in the direction of flow of the molten iron, and, second, that the convergence of the side walls of the chute channel has not been

such as to take into account the conditions which would tend to bring about the progressive narrowing of the stream of metal with a minimum of resistance tending to produce turbulence in the stream.

While practical considerations do not in all cases permit of giving the chute channel a theoretically perfect contour and while in all cases the chute channel must be broad enough at its top to receive within its side walls the stream of metal delivered by the ladle and must be narrowed at its delivery end to a breadth substantially the same as that of the channel in the trough into which the chute delivers the metal stream, we have found it practicable in all cases to practically eliminate the danger of forming a spray of metal issuing from the surface of the metal stream and to so greatly reduce the turbulence in the stream as to eliminate the spraying of metal from the chute, the occurrence of splashes from the sides of the trough and the occurrence of splashes when the metal contacts with the mold by forming the chute with a bottom longitudinal contour of such character that at or about the point where the metal first contacts with the chute the inclination of the chute to the vertical would not exceed 30° and which receiving surface is continued as a substantially geometric curve drawn between a tangent of the same angular inclination to the vertical as that of the receiving portion of the chute and a tangent, at or near the delivery end of the chute, forming a slight angle with the horizontal and lying substantially parallel to the trough. By preference the curve should be of such a character that its tangent at its upper end is considerably less than 30° and it is generally practicable to use a curve the upper tangent of which will form an angle with the vertical of between 40° and 20°. By preference the geometric curve is continued to the point of impact of the falling stream of metal but as it is desirable that the curve should flatten out, so to speak, as it approaches its lower tangent it is desirable that the length of its upper tangent between its point of contact with the curve and its point of intersection with the lower tangent should be shorter than the length of the lower tangent between its point of contact with the upper tangent and its point of contact with the curve.

While any geometric curvature of the chute conforming to the conditions above indicated will give improved results, we have found that the most effective and satisfactory curve is that of a parabola which, especially where the curvature progressively diminishes as the delivery end of the chute is approached, will, we have found, bring about a flow of the molten metal with minimum turbulence and minimum tendency to throw out a spray of metal from the surface.

With regard to the contour of the side walls of the chute channel, these walls must be spaced apart at the line of impact of the metal falling from the chute by a distance equal to the breadth of the stream of metal while at the delivery end of the chute and preferably somewhat in advance of the delivery end, the breadth of the channel between the side walls must be essentially the same as the breadth of the channel in the trough into which the metal is delivered. The vertical height of the chute must be such as, in view of the general inclination and shape of the channel formed in the chute, will result in imparting to the stream of molten metal at the delivery end of the chute a velocity which will

carry the stream of metal into and through the trough at a rate of speed which will keep the level of the stream in the trough sufficiently below the top edges of the channel to avoid the risk of the metal spilling over the sides of the trough and, at the same time, to secure the delivery of the metal to the spout at the end of the trough at such moderate velocity and absence of turbulence as will not bring about splashing of the metal as it comes in contact with the mold. It will be understood, of course, that the ladle delivering the molten metal to the chute and its actuating mechanism should be of such a character that it is adapted to deliver its contents at an even rate, is necessarily so located and constructed that its pouring lip will, under all conditions, lie at a somewhat higher level than that portion of the chute to which it delivers a stream of metal so that the metal stream as it first contacts with the chute is already moving with a velocity determined by the rate of pouring and the height of its fall from the lip of the ladle; this involves that the breadth of the chute at the point of contact should be somewhat less than the length of the lip and, consequently, that the forces we have mentioned tending to diminish the cross-sectional area of the stream and change its form will have resulted, at the time the stream contacts with the chute, in somewhat narrowing the breadth of the stream but the distance through which the metal falls freely from the ladle is in practice made as short as practicable and the chute itself is relied upon to effect in great part the necessary narrowing of the breadth of the stream to a breadth corresponding to the breadth of the channel in the trough and the problem which confronted us with regard to the contour of the side walls of the trough channel was to give them such a shape as would effect the necessary narrowing of the stream of metal under conditions which would not bring about a spraying of the metal or undue turbulence in the flowing stream. In considering this problem we had to take into account that in casting pipes of different sizes, it is necessary to use chutes of varying vertical height with, of course, corresponding changes in the vertical height of the ladle above the level of the trough and that practical considerations do not always make it possible to use chutes of a horizontal length which would be theoretically best adapted for use. Protracted experimentation indicated that a convergence of the side walls which would narrow the stream of molten metal approximately as the stream would narrow in falling freely through a vertical distance equal to the length of the chute between the point where the metal contacts with it and the point where it is delivered would affect the narrowing of the stream with but little tendency to produce turbulence but, as we have explained, the breadth of the stream at the delivery end of the chute must be practically the same as that of the channel into which the metal is delivered and the breadth of the stream delivered by the ladle to the upper part of the chute cannot be arbitrarily limited though in many cases it is practicable to so construct the ladle and its pouring lip that it will deliver to the chute a stream of metal the breadth of which at the point of impact will not exceed eight times the breadth of the stream at the delivery end of the chute and we have found it highly advantageous that this ratio should not be exceeded and, where practicable, should be less. In most cases it is not practicable to give the chute a horizontal length such

as would be theoretically desirable but we have discovered that in all cases a reasonably satisfactory nonturbulent flow of the molten metal through and from the chute can be secured by giving to the side walls of the channel in the chute the form of converging geometric curves upon which the trace of the center line of the chute channel, when developed to its true length on a horizontal plane, will have a curvature at the upper end of the curve corresponding approximately to the point of impact of the metal and will have a tangent forming an angle with the center line of the chute not to exceed 30° and which, at the delivery end of the chute, will have a tangent substantially parallel to the center line of the chute. By preference, and when compatible with the angularity of the upper tangent to the center line of the chute, the tangent lines from their point of contact with the curve to their point of intersection with each other should be approximately of the same length and while improved results are obtainable with practically all curves drawn in accordance with the provisions above given, we have found that the most effective curvature for the side walls is that of a parabola and, in speaking of the curvature of the side walls, it should be understood that we are speaking of the curvature of the trace of the center line of the chute upon the surface of the side walls as such trace is developed on a horizontal plane as this is the curvature of the side wall which is actually followed by the flowing metal and this is the improved construction as effecting a smooth and nonturbulent flow of the metal.

It will, of course, be understood that while improved results are obtainable by giving to the bottom of the channel the form which we have described, irrespective of the curvature of the side walls and while, again, improved results are obtainable by giving to the side walls the construction which we have described, irrespective of the form of the surface of the chute, and, for the best results, both the bottom and side walls of the chute channel should be given the forms which we have indicated and, again, we would point out that while in most cases it is advantageous that the curves of the center line of the chute and of its side walls should continue to approximate the delivery end of the chute, our invention can be advantageously used with chutes in which the bottom curvature of the chute channel merges into a straight line and in which the side walls, to a corresponding distance, may run parallel to each other before merging into curves which we have described.

With regard to the form of the chute above the line of impact of the metal falling upon it, this, it will be understood, is immaterial so far as our invention is concerned and will be determined by practical considerations involving the necessary clearance of the ladle lip.

It will, of course, be understood that in describing the curvature of the center line and side walls of the chute as geometrical curves we are not to be understood as limiting ourselves to truly mathematical curves as such perfection of curvature is hardly practical of attainment but curves approximating the curvatures which we have described are entirely practicable and can follow within the scope of our invention.

As examples of chutes which we have designed and successfully used in practice, we will give the following:

Example one

75 Height of chute, $16\frac{1}{2}$ inches; horizontal length

of chute, 43 inches; distance between side walls at line of impact of metal, 18 inches; breadth of channel at delivery end of chute, 3 inches; center line of channel, a parabolic curve drawn between a tangent at its upper end forming an angle of 15° with the vertical and a tangent at its lower end forming an angle of $3\frac{1}{2}^\circ$ with the horizontal; curvature of side walls along the trace of the center line upon said walls as developed in a horizontal plane; parabolic curves drawn between the tangent at the upper end of the chute forming an angle of 18° with the center line of the chute and a tangent at the delivery end of the chute lying parallel to the center line.

Example two

15

Height of chute, $23\frac{1}{4}$ inches; horizontal length of chute, $36\frac{1}{4}$ inches; distance between side walls at line of impact of metal, 12 inches; breadth of channel at delivery end of chute, $2\frac{1}{2}$ inches; center line of channel, a parabolic curve drawn between a tangent at its upper end forming an angle of 30° with the vertical and a tangent at its lower end forming an angle of 3° with the horizontal; curvature of side walls along the trace of the center line upon said walls as developed in a horizontal plane; parabolic curves drawn between the tangent at the upper end of the chute forming an angle of 13° with the center line of the chute and a tangent at the delivery end of the chute lying parallel to the center line.

Example three

Height of chute, $18\frac{1}{2}$ inches; horizontal length of chute, $53\frac{1}{2}$ inches; distance between side walls at line of impact of metal, 18 inches; breadth of channel at delivery end of chute, 3 inches; center line of channel, a parabolic curve drawn between a tangent at its upper end forming an angle of 20° with the vertical and a tangent at its lower end forming an angle of 2° with the horizontal; curvature of side walls along the trace of the center line upon side walls as developed in a horizontal plane; parabolic curves drawn between the tangent at the upper end of the chute forming an angle of 15° with the center line of the chute and a tangent at the delivery end of the chute lying parallel to the center line.

50

As heretofore constructed, in machines of the kind to which our invention relates, the trough has extended forward beyond the point at which the lower end of the chute enters it and to a supporting and adjusting structure located in the structure extending upward from the bed of the machine and supporting the ladle at its top, a further support and adjustment of the trough being provided for nearer the point where the trough enters the mold in the more advanced position of the mold and the chute has been supported in and by the trough at its lower end and by adjusting screws located at the top of the ladle supporting structure and the chute has been kept in abutting contact with the lining blocks with which the trough is provided by a spring located in the rear portion of the trough and abutting against the shoulder formed on the chute and lying in the trough. It is impracticable in these older constructions to form a chute with the channels substantially conforming to our improved construction nor do the means heretofore employed for supporting the chute reliably secure an accurate abutment of the delivery end of the trough against the lin-

55

60

65

70

75

ing blocks and to provide a structure suitable for use in connection with our improved chutes and a more reliable way of securing and maintaining a proper alignment of the chute with the lining blocks of the trough we construct the trough so that it will not extend forward beneath the chute to a greater extent than is necessary to afford a seat for the delivery end of the chute and secure to the front end of the trough a forwardly extending supporting structure preferably formed by beams firmly secured to the sides of the trough the side walls of which structure are so spaced apart as to afford clearance for the portions of the chute structure which may extend between them and which are, moreover, so spaced apart as to afford a good supporting base upon which lugs or feet extending down from the upper and wider portions of the chute may rest so that the chute is supported entirely upon the front end of the trough and upon the side walls of the trough supporting structure. Our new construction further involves the provision of a guideway supported by the trough supporting structure upon which are slidingly supported and guided spring caps, one abutting against a shoulder formed on the chute and the other against a suitable support and holding between them a spring adjusted to maintain the delivery end of the chute in contact with the lining blocks of the trough and, to protect the spring and spring supporting structure from being fouled by molten metal or foundry dirt, we secure to the side walls of the trough supporting structure a cover plate extending over the spring structure and our improvements will perhaps be better understood as further described in connection with the drawings in which.

Figure 1 is an elevation of a centrifugal pipe casting machine embodying our improvements taken on a central longitudinal section.

Figure 2 is a fragmentary plan view of the chute, the end of the trough on which it is supported and a portion of the trough supporting structure, shown on a larger scale than Fig. 1.

Figure 3 is a sectional elevation of a part of the structure shown in Fig. 1, on a larger scale.

Figure 4 is a cross-sectional view on the line 4-4 of Fig. 3.

Figure 5 is an elevation viewed from the left of the chute and trough supporting structure.

Figure 6 is a cross-sectional view on the line 6-6 of Fig. 3.

Figures 7 to 16 are cross-sectional views taken as indicated on the lines 7-7, 8-8, 9-9, 10-10, 11-11, 12-12, 13-13, 14-14, 15-15, and 16-16, of Fig. 3.

Figure 17 is a diagram illustrative of a method of laying out the curves of the side walls of the chute in what we believe to be their most effective curvature, and

Figure 18 is a diagram illustrating an effective way of laying out the curve of the center line of the chute in what we believe to be its most effective curvature.

A indicates the framing forming the base of the pipe casting machine, A¹ an elevated structure or tower supporting the ladle indicated at A², A² indicating the lip of the ladle. Mechanism for tipping the ladle is indicated at A³ and, as it forms no part of our invention, need not be described in detail. A⁴ indicates the carriage supported on wheels A⁴ and supporting a water box A⁵ traversed by a rotatable mold A⁶ to which 75 rotary motion is imparted by a motor A⁷ and

gears A⁸. Reciprocating motion is given to the carriage by a cylinder and piston as indicated at A⁹. In all of the above noted features the apparatus is of usual construction. B indicates the trough structure made up, as shown, of an outer 5 casing B¹ which is divided into a central or trough structure and water circulating chambers B³, B³, by partitions indicated at B⁴, B⁴. B⁵, B⁵, indicate water supply pipes for introducing water into the water circulating chambers, B⁶, B⁶, indicating lining blocks in the trough section through which is formed the trough channel and B⁷ indicates the terminal or delivery spout of the trough. In all of the above noted features the trough structure is of well 10 known construction but as heretofore constructed the described trough structure, with the exception of the lining blocks, is continued forwardly, that is to say, toward the structure supporting the ladle to a support, whereas in our present 15 construction the trough is continued forwardly only to a sufficient distance to afford a seat and support for the end of the chute to be described. In our new construction, supporting means for the trough are attached to its forward end and 20 formed with side walls spaced apart by a sufficient distance, greater than that of the trough proper, to afford clearance to the portions of the chute which extend between the walls and a firm 25 support for the front or upper portion of the chute and, as shown, the trough supporting structure consists of beams C, C, firmly secured to the front end of the trough as shown in Fig. 3. To the front end of these beams is secured a transverse channel beam indicated at C¹, to 30 which is firmly secured a projecting stud, indicated at C², which extends into a space a¹ formed in the tower A¹ and adjusted therein as by means of adjusting screws indicated at C³. A further 35 support for the trough and trough supporting structure is indicated at D and, here again, adjusting screws, indicated at D¹, are provided for the proper alignment of the trough.

Returning to the structure for the support of the front end of the trough, C⁴, C⁴, are plates secured to the lower sides of the beams C, C, and supporting in turn a central longitudinal guideway C⁵, indicated as a channel beam. Supported on and guided by this channel beam are spring caps C⁶, C⁶, one abutting against a shoulder on the chute as will be described and the other abutting against an adjusting screw indicated at C⁷. C⁸ indicates a spring, the ends of which are engaged in the spring caps, and C⁹ is a cover plate extending between the beams C, C, and serving as a protection to the spring structure described.

E indicates our new chute construction, the chute being provided to receive the metal as it is poured out from the ladle and deliver it to the front end of the trough. Chutes for this purpose have heretofore been in use and have been provided with side walls spaced apart at their upper ends by a distance greater than the breadth of the stream of metal delivered from the ladle and at their lower ends by a distance equal to the breadth of the channel in the trough into which the chute delivers its metal. The height of the channel through which the molten metal runs has been such as to impart to the stream of molten metal sufficient velocity to insure that the stream will traverse the length of the trough and be delivered at its end in a stream of sufficient volume to supply the mold and bring about the production of a pipe of the desired 70 75 80 85 90 95 100

diameter and wall thickness but, as we have pointed out, chutes as heretofore constructed have brought about such turbulence in the stream of molten metal as to lead to the production of an appreciable percentage of defective pipe castings and a prime object of our invention has been the development of a chute which will impart the necessary velocity to the stream of metal passing through it and the necessary change in cross-sectional form with a minimum degree of turbulence in the flowing stream of metal and with this object in view we form the bottom of the chute channel so that approximately at the point indicated at E^1 where the falling stream of metal first contacts with the chute it will form an angle of not more than 30° with the vertical, a smaller angle being preferable and we continue the bottom of the chute channel, the center line of which is indicated at E^2 , as a geometric curve merging into the receiving surface at the top of the chute and having at its upper end a tangent lying in the receiving face of the channel and having, of course, the same angular inclination with the vertical and another tangent at the delivery end of the chute which is approximately horizontal and preferably forming only such angle with the horizontal as is the case with the channel in the trough to which the chute delivers its metal. The curved surface of the chute channel, as is indicated at E^3 , and which preferably extends from the point of impact of the metal, indicated at E^1 , has a continuous curve to the delivery end of the chute and, for the best results, this curve should be a parabolic curve, or curved segment, although other geometric curves filling the same condition as to tangency may be used with advantage as compared with previously existing contours of the chute surface. The essential conditions to have in view are, that the metal falling from the ladle should not strike a chute surface of a greater angularity to the vertical than 30° and that this receiving surface should merge and advantageously as promptly as possible into a smooth running continuous curve, a tangent to which at the delivery end of the chute should lie practically parallel to the channel in the trough. It is, however, decidedly advantageous that the curvature of the chute channel as it approaches the delivery end of the chute should be of progressively decreasing curvature and this, where other conditions make it practicable, should be provided for by so constructing the chute that the tangent line from the upper end of the curve to its point of intersection with the tangent line from the lower end of the curve should be shorter than the length of the tangent line from the lower end of the curve to the point of intersection. In Fig. 18, we have illustrated the laying out of the center line of the chute in a parabolic curve. The broken line F indicates the vertical height of the chute and the partly broken and partly full line F^1 and F^3 , of which the full line portion F^3 is a tangent line, indicate the horizontal length of the chute. The tangent to the upper end of the curve is indicated at F^2 and the tangent to the lower end of the curve is indicated at F^4 , their point of intersection being indicated at F^5 . In laying off the parabolic curve between these two tangents, a convenient and satisfactory plan is to divide the two tangent lines F^2 and F^3 into the same number of divisions as indicated on the upper tangent line at f^1 , f^2 , f^3 , f^4 , f^5 , f^6 and f^7 and the lower tangent line into an equal number of divisions as indicated at g^1 , g^2 , g^3 , g^4 , g^5 , g^6 and g^7 , then drawing straight

lines, as indicated, from f^1 to g^1 , from f^2 to g^2 , etc. These lines will form tangents of a parabolic curve and facilitate the laying out of such a curve for the use of the pattern makers.

The side walls of the chute channel which are indicated at E^4 , E^5 , are necessarily spaced apart at their upper ends by a distance slightly greater than the breadth of the stream of metal falling upon the chute from the ladle and necessarily converge so that at the delivery end of the chute they are distant from each other by approximately the same distance as the width of the trough channel. The function of the side walls is to contract the stream of molten metal which is, for the greater part of its passage through the chute, moving with accelerating velocity and consequently with progressive contraction of its cross-sectional area. The forces of molecular attraction and surface tension which tend to bring a falling stream of liquid of irregular shape to a form having a circular cross-section are also, to some extent, operative even when the liquid is flowing over an inclined surface although opposed in such a case by the weight of the metal tending to spread it out over its supporting surface. Our investigations have led us to believe that a side wall construction in which the walls would converge toward each other approximately as the sides of the falling stream would converge in falling through a distance approximating the vertical distance between point of first contact and point of delivery, would bring about a narrowing of the stream with the least possible turbulence but in practice the height and length of the chute channel are determined by other considerations and in developing a construction of the side walls of the chute which will in practice produce a minimum turbulence in the flow of the molten iron we have had to take all practical considerations into account, inclusive of such changes in the height and length of chutes as are found necessary in the casting of pipes of different diameters and varying wall thickness as well as the adapting of our improved chutes for substitution in pipe casting machinery already existent. The essential curvature of the side walls is of that portion of the walls with which the metal actually contacts in the passage through the chute channel, that is to say, of portions of the side walls lying approximately opposite to the center line of the chute and following the curvature of said center line, said portions of the side walls having, so to speak, a double curvature, that is to say, curving downward from the upper portion of the chute to its delivery end and inward toward the center line of the chute and we have found that an effective and satisfactory curvature of the side walls should be such that the trace of their surfaces upon the bottom surface of the chute when developed to its true length upon a horizontal plane, will form a geometric curve, preferably a parabolic curve lying between tangents, the upper one of which will form an angle of not to exceed 30° with the developed center line of the chute and the lower one of which, at the delivery end of the chute, will be essentially parallel with the center line. Where practicable the length of the tangent lines from the points of tangency to their point of intersection should be substantially equal, though in no case should the angle, which the upper tangent forms to the center line of the chute, be greater than 30° .

In Fig. 17, we have provided a diagram illustrating a convenient way of laying out the curva-

ture of the side walls of the chute with parabolic curves along the line of flow of the metal where it contacts with the side walls. In this diagram, E, E³, represent the development of the center line of the chute to its true length as a straight line between the point of first contact and point of delivery. At the upper end of this line we erect a right angle line indicated at H and of a length equal to half the breadth of the chute channel at or about the point of contact of the molten metal and at the lower end of the developed center line corresponding to the delivery end of the chute we erect a right angle line H¹ of a length equal to half the breadth of the chute channel at this point. From the end of the line H, which corresponds approximately to the point on the side wall where the metal stream from the ladle first contacts with it, we draw a line H² forming an angle of not more than 30° with the center line E, E³, and from the end of the line H¹ we draw a line H³ parallel to the center line and we then lay out a geometric curve H⁴ of such a character that the lines H² and H³ will form tangents to the curve at the points on the lines H and H¹ from which such tangent lines are drawn and, subject to the stated limitation as to the angle which the tangent line H² must form with the center line of the chute, we draw the lines H² and H³ at such angularity with each other that they will intersect, as indicated at H⁵, at a point equi-distant from the two points of tangency to which the tangents are drawn. The curvature of the developed trace of the center line upon the side walls is preferably that of a parabolic curve which is conveniently drawn, as indicated in Fig. 17, by dividing the tangent H² into any desired number of equal parts, as indicated at h¹, h², h³, h⁴, h⁵, h⁶ and h⁷, and dividing the tangent line H³ into the same number of equal parts as indicated at i¹, i², i³, i⁴, i⁵, i⁶ and i⁷, and then drawing a series of straight lines connecting the division points h¹ and i¹, h² and i², etc., which lines will form tangents to a parabolic curve and practically facilitate the laying out of such a curve for the use of the pattern maker.

In referring to other geometric curves as possible substitutes for parabolic curves in the center line of the chute and in the contour of the side walls as developed we have in mind such curves as can be laid out between intersecting tangents and while it is true that such curves, other than parabolic curves, will give improved results as compared with the contour lines of chutes as previously used in centrifugal pipe casting machines, we have found that the parabolic curves are decidedly better than others as bringing about the flow of molten metal through the chute with the minimum of turbulence.

The delivery end of the chute indicated at E⁵ is formed, as we have stated, with its channel conformed in cross-section to the shape of the channel formed through the lining blocks B⁶ of the trough and with its outer dimensions conformed to the shape of the front end of the trough B in which this delivery end of the chute is supported, with its extreme end abutting against the front lining block of the trough and it is important that the fitting of the end of the chute against the front lining block should be reasonably accurate and not affected by adjustments of the trough and to secure an accurate and permanent alignment of the chute with the trough we provide the front or upper end of the chute with downwardly extending supporting legs as indicated at E⁶, E⁷, which engage and

rest upon the tops of the side walls of the supporting structure C, thereby insuring in all adjustments of the trough and its supporting structure that the proper alignment of the chute and trough shall be maintained.

On the underside of the chute we provide a spring abutment shoulder indicated at E⁷, against which the rear spring cap C⁶ abuts and the necessary compression is given to the spring C⁸ by shifting the front spring cap C⁶ by the adjusting screw C⁷.

The assembly and operation of our improved machine will be clear to those skilled in the art from the above description and need not, we believe, be further detailed.

Having now described our invention, what we claim as new and desire to secure by Letters Patent, is:

1. In centrifugal pipe casting apparatus comprising a rotatable mold, a conduit for the delivery of molten metal extending into the mold, a ladle adapted to contain and deliver molten metal located in front of and at a higher level than the mold, the combination therewith of an inclined chute adapted to receive the metal from the ladle and deliver it to the conduit entering the mold, which chute is formed with a bottom contour which, at approximately the point where the metal from the ladle first contacts with the chute, is inclined to the vertical at an angle not exceeding 30° and which is continued as a geometric curve of progressively decreasing curvature having at its upper end a tangent coinciding in angular inclination with the angular inclination of the chute at the point of impact of the metal and having at the lower end of the curve an approximately horizontal tangent.

2. In centrifugal pipe casting apparatus comprising a rotatable mold, a conduit for the delivery of molten metal extending into the mold, a ladle adapted to contain and deliver molten metal located in front of and at a higher level than the mold, the combination therewith of an inclined chute adapted to receive the metal from the ladle and deliver it to the conduit entering the mold, which chute is formed with a bottom contour which, at approximately the point where the metal from the ladle first contacts with the chute, is inclined to the vertical at an angle not exceeding 30° and which is continued as a substantially parabolic curve drawn between a tangent of the same angular inclination to the vertical as that of the receiving portion of the chute and an approximately horizontal tangent, at or near the delivery end of the chute.

3. Apparatus as called for in claim 2, in which the parabolic curvature of the bottom contour of the chute is of such a character that the length of the tangent drawn from the upper end of the parabolic curve to a point of intersection with the tangent line drawn from the lower end of the parabolic curve will be less than that of the tangent line drawn from the lower point of the curve to the point of intersection.

4. Apparatus as called for in claim 2, in which the parabolic bottom curvature of the chute is continued at its upper end to approximately the point where the metal from the ladle first contacts with the chute.

5. In centrifugal pipe casting apparatus comprising a rotatable mold, a conduit for the delivery of molten metal extending into the mold, a ladle adapted to contain and deliver molten metal located in front of and at a higher level than the mold, the combination therewith of an

inclined chute adapted to receive the metal from the ladle and deliver it to the conduit entering the mold, which chute is formed with a bottom contour which, at approximately the point where the metal from the ladle first contacts with the chute, is inclined to the vertical at an angle not exceeding 30° and which is continued as a geometric curve having at its upper end a tangent coinciding in angular inclination with the angular inclination of the chute at the point of impact of the metal and having at the lower end of the curve an approximately horizontal tangent, further characterized in that the chute is provided with side walls which, at the point where the metal from the ladle contacts with the chute, are spaced apart by approximately the breadth of the metal stream falling from the lip of the ladle and at the delivery end of the chute by the breadth of the stream of metal which the chute is designed to deliver and which side walls progressively converge in relatively convex curves of such a character that the trace of the bottom line of the chute thereupon will, when developed to its true length upon a horizontal plane, form a geometric curve drawn between a tangent to the upper end of the curve forming an angle of not more than 30° with the center line of the chute and a tangent to the lower end of the curve lying parallel to said center line.

6. In centrifugal pipe casting apparatus comprising a rotatable mold, a conduit for the delivery of molten metal extending into the mold, a ladle adapted to contain and deliver molten metal located in front of and at a higher level than the mold, the combination therewith of a chute adapted to receive the metal from the ladle and deliver it to the conduit entering the mold, which chute is formed with a downwardly inclined channel for the passage of molten metal having side walls which, at the point where the metal from the ladle contacts with the chute, are spaced apart by a distance not materially greater than the breadth of the stream of molten metal delivered from the lip of the ladle at the time it contacts with the chute and which, at or near the delivery end of the chute, are spaced apart by a distance substantially the same as the breadth of the conduit into which the chute delivers the molten metal, each of said converging side walls having a surface contour which passes through a point at or adjacent to that at which the metal of the ladle first contacts with the side wall and through a point at the lower end of the chute which is distant from the center line of the chute by half its width, said surface contour being such that the trace formed by it upon the surface contour of the bottom of the chute, when developed to its true length, will be a curve, a tangent to which at the point where the metal first contacts with the wall of the chute will form an angle with the center line of the chute of not more than 30° and at the point at the lower end of the wall will have a tangent essentially parallel to the center line.

7. In centrifugal pipe casting apparatus comprising a rotatable mold, a conduit for the delivery of molten metal extending into the mold, a ladle adapted to contain and deliver molten metal located in front of and at a higher level than the mold, the combination therewith of a chute adapted to receive the metal from the ladle and deliver it to the conduit entering the mold, which chute is formed with a downwardly

inclined channel for the passage of molten metal having side walls which, at the point where the metal from the ladle contacts with the chute, are spaced apart by a distance not materially greater than the breadth of the stream of molten metal delivered from the lip of the ladle at the time it contacts with the chute and which, at or near the delivery end of the chute, are spaced apart by a distance substantially the same as the breadth of the conduit into which the chute delivers the molten metal, each of said converging side walls having a surface contour which passes through a point at or adjacent to that at which the metal of the ladle first contacts with the side wall and through a point at the lower end of the chute which is distant from the center line of the chute by half its width, said surface contour being such that the trace formed by it upon the surface contour of the bottom of the chute, when developed to its true length, will be a curve, a tangent to which at the point where the metal first contacts with the wall of the chute will form an angle with the center line of the chute of not more than 30° and at the point at the lower end of the wall will have a tangent essentially parallel to the center line, said side wall curvature being further characterized in that the tangents from the upper and lower ends of the curved wall intersect each other at a point approximately equi-distant from the two points of tangency.

8. In centrifugal pipe casting apparatus comprising a rotatable mold, a conduit for the delivery of molten metal extending into the mold, a ladle adapted to contain and deliver molten metal located in front of and at a higher level than the mold, the combination therewith of a chute adapted to receive the metal from the ladle and deliver it to the conduit entering the mold, which chute is formed with a downwardly inclined channel for the passage of molten metal having side walls which, at the point where the metal from the ladle contacts with the chute, are spaced apart by a distance not materially greater than the breadth of the stream of molten metal delivered from the lip of the ladle at the time it contacts with the chute and which, at or near the delivery end of the chute, are spaced apart by a distance substantially the same as the breadth of the conduit into which the chute delivers the molten metal, each of said converging side walls having a surface contour which passes through a point at or adjacent to that at which the metal of the ladle first contacts with the side wall and through a point at the lower end of the chute which is distant from the center line of the chute by half its width, said surface contour being such that the trace formed by it upon the surface contour of the bottom of the chute, when developed to its true length on a horizontal plane, will be a substantially parabolic curve, a tangent to which at the point where the metal first contacts with the wall of the chute will form an angle with the center line of the chute of not more than 30° and at the point at the lower end of the wall will have a tangent essentially parallel to the center line.

9. In centrifugal pipe casting apparatus comprising a rotatable mold, a conduit for the delivery of molten metal extending into the mold, a ladle adapted to contain and deliver molten metal located in front of and at a higher level than the mold, the combination therewith of a chute adapted to receive the metal from the ladle and deliver it to the conduit entering the mold, which chute is formed with a downwardly

inclined channel for the passage of molten metal having side walls which, at the point where the metal from the ladle contacts with the chute, are spaced apart by a distance not materially greater than the breadth of the stream of molten metal delivered from the lip of the ladle at the time it contacts with the chute and which, at or near the delivery end of the chute, are spaced apart by a distance substantially the same as the breadth of the conduit into which the chute delivers the molten metal, each of said converging side walls having a surface contour which passes through a point at or adjacent to that at which the metal of the ladle first contacts with the side wall and through a point at the lower end of the chute which is distant from the center line of the chute by half its width, said surface contour being such that the trace formed by it upon the surface contour of the bottom of the chute, when developed to its true length on a horizontal plane will be a substantially parabolic curve, a tangent to which at the point where the metal first contacts with the wall of the chute will form an angle with the center line of the chute of not more than 30° and at the point at the lower end of the wall will have a tangent essentially parallel to the center line, said side wall curvature being further characterized in that the tangents from the upper and lower ends of the curved wall will intersect each other at a point approximately equi-distant from the two points of tangency.

10. In centrifugal pipe casting apparatus comprising a rotatable mold, a conduit for the delivery of molten metal extending into the mold, a ladle adapted to contain and deliver molten metal located in front of and at a higher level than the mold, the combination therewith of a chute adapted to receive the metal from the ladle and deliver it to the conduit entering the mold, which chute is formed with a bottom contour which, at approximately the point where the metal from the ladle first contacts with the chute, is inclined to the vertical at an angle not exceeding 30° and which is continued as a substantially parabolic curve drawn between a tangent of the same angular inclination to the vertical as that of the receiving portion of the chute and a tangent, at or near the delivery end of the chute, forming a slight angle with the horizontal, said chute being further characterized in that the channel formed therein for the passage of molten metal is formed with side walls which, at the point where the metal from the ladle contacts with the chute, are spaced apart by a distance not materially greater than the width of the stream of molten metal at the time it contacts with the chute and which, at or near the delivery end of the chute, are spaced apart by a distance substantially the same as the breadth of the conduit into which the chute delivers the molten metal, each of said converging side walls having a surface contour which passes through a point at or adjacent to that at which the metal of the ladle first contacts with the side wall and through a point at the lower end of the chute which is distant from the center line of the chute by half its width, said surface contour being such that the trace formed by it upon the surface contour of the bottom of the chute, when developed to its true length, will be a parabolic curve, a tangent to which at the point where the metal first contacts with the wall of the chute will form an angle with the center line of the chute of not more than 30° and at the point at the lower end of the wall will have a tangent essentially parallel to the center line, said tangents in the development subject to the angular limitation intersecting each other at a point approximately equi-distant from the two points on the curve to which the tangents are drawn.

11. In centrifugal pipe casting apparatus comprising a trough or runner having a delivery spout at its end, a relatively reciprocable centrifugal mold, a ladle for containing and delivering molten metal located above and in front of the mold and trough, the combination therewith of a chute adapted to receive the metal from the ladle and deliver it to the trough and through the trough to the mold, having a channel which at its delivery end conforms to the shape of the channel in the trough, which chute is formed with a bottom contour which, at approximately the point where the metal from the ladle first contacts with the chute, is inclined to the vertical at an angle not exceeding 30° and which is continued as a substantially parabolic curve drawn between a tangent of the same angular inclination to the vertical as that of the receiving portion of the chute and a tangent at the lower end of the chute substantially parallel to the trough.

12. In centrifugal pipe casting apparatus comprising a trough or runner having a delivery spout at its end, a relatively reciprocable centrifugal mold, a ladle for containing and delivering molten metal located above and in front of the mold and trough, the combination therewith of a chute adapted to receive the metal from the ladle and deliver it to the trough and through the trough to the mold, which chute is formed with a downwardly inclined channel for the passage of molten metal having side walls which, at the point where the metal from the ladle contacts with the chute, are spaced apart by a distance not materially greater than the width of the stream of molten metal at the time it contacts with the chute and which, at the delivery end of the chute, are spaced apart by a distance substantially the same as the breadth of the channel in the trough into which the chute delivers the molten metal, each of said converging side walls having a surface contour which passes through a point at or adjacent to that at which the metal of the ladle first contacts with the side wall and through a point at the lower end of the chute which is distant from the center line of the chute by half its width, said surface contour being such that the trace formed by it upon the surface contour of the bottom of the chute, when developed to its true length, will be a parabolic curve, a tangent to which at the point where the metal first contacts with the wall of the chute will form an angle with the center line of the chute of not more than 30° and at the point at the lower end of the wall will have a tangent essentially parallel to the center line, said tangents in the development subject to the angular limitation intersecting each other at a point approximately equi-distant from the two points on the curve to which the tangents are drawn.

13. In centrifugal pipe casting apparatus comprising a trough or runner having a delivery spout at its end, a relatively reciprocable centrifugal mold, a ladle for containing and delivering molten metal located above and in front of the mold and trough, the combination therewith of a chute adapted to receive the metal from the ladle and deliver it to the trough and through the trough to the mold, having a channel which at its delivery end conforms to the shape of the channel in the trough, which chute is formed with a bottom contour which, at approximately the point where the metal from the ladle first contacts with the chute, is inclined to the vertical at an angle not exceeding 30° and which is continued as a substantially parabolic curve drawn between a tangent of the same angular inclination to the vertical as that of the receiving portion of the chute and a tangent at the lower end of the chute substantially parallel to the trough.

14. In centrifugal pipe casting apparatus comprising a trough or runner having a delivery spout at its end, a relatively reciprocable centrifugal mold, a ladle for containing and delivering molten metal located above and in front of the mold and trough, the combination therewith of a chute adapted to receive the metal from the ladle and deliver it to the trough and through the trough to the mold, which chute is formed with a downwardly inclined channel for the passage of molten metal having side walls which, at the point where the metal from the ladle contacts with the chute, are spaced apart by a distance not materially greater than the width of the stream of molten metal at the time it contacts with the chute and which, at the delivery end of the chute, are spaced apart by a distance substantially the same as the breadth of the channel in the trough into which the chute delivers the molten metal, each of said converging side walls having a surface contour which passes through a point at or adjacent to that at which the metal of the ladle first contacts with the side wall and through a point at the lower end of the chute which is distant from the center line of the chute by half its width, said surface contour being such that the trace formed by it upon the surface contour of the bottom of the chute, when developed to its true length, will be a parabolic curve, a tangent to which at the point where the metal first contacts with the wall of the chute will form an angle with the center line of the chute of not more than 30° and at the point at the lower end of the wall will have a tangent essentially parallel to the center line, said tangents in the development subject to the angular limitation intersecting each other at a point approximately equi-distant from the two points on the curve to which the tangents are drawn.

the trough to the mold, which chute is formed with a bottom contour which, at approximately the point where the metal from the ladle first contacts with the chute, is inclined to the vertical 5 at an angle not exceeding 30° and which is continued as a substantially parabolic curve drawn between a tangent of the same angular inclination to the vertical as that of the receiving portion of the chute and a tangent, at or near the 10 delivery end of the chute, forming a slight angle with the horizontal, said chute being further characterized in that the channel formed therein for the passage of molten metal is formed with side walls which, at the point where the 15 metal from the ladle contacts with the chute, are spaced apart by a distance not materially greater than the width of the stream of molten metal at the time it contacts with the chute and which, at the delivery end of the chute, are 20 spaced apart by a distance substantially the same as the breadth of the channel in the trough into which the chute delivers the molten metal, each of said converging side walls having a surface contour which passes through a point at or 25 adjacent to that at which the metal of the ladle first contacts with the side wall and through a point at the lower end of the chute which is distant from the center line of the chute by half its width, said surface contour being such that 30 the trace formed by it upon the surface contour of the bottom of the chute, when developed to its true length, will be a parabolic curve, a tangent to which at the point where the metal first contacts with the wall of the chute will form 35 an angle with the center line of the chute of not more than 30° and at the point at the lower end of the wall will have a tangent essentially parallel to the center line, said tangents in the development subject to the angular limitation 40 intersecting each other at a point approximately equi-distant from the two points on the curve to which the tangents are drawn.

14. In centrifugal pipe casting apparatus comprising a trough or runner having a delivery 45 spout at its end, a relatively reciprocable centrifugal mold, a ladle for containing and delivering molten metal located above and in front of the mold and trough, the combination therewith of a chute adapted to receive the metal from the ladle and deliver it to the trough and through the trough to the mold, having a channel which, at its delivery end, conforms to the shape of the channel in the trough, which chute is formed with a bottom contour which, at approximately 55 the point where the metal from the ladle first contacts with the chute, is inclined to the vertical at an angle not exceeding 30° and which is continued as a substantially geometric curve drawn between a tangent of the same angular 60 inclination to the vertical as that of the receiving portion of the chute and a tangent at the lower end of the chute substantially parallel to the trough, and further characterized in that the delivery end of the chute enters and is supported

by the front end of the trough and the trough is provided with a forwardly extending angularly adjustable supporting structure having side walls which at their upper portions are spaced apart by a greater distance than that of the side walls 5 of the trough structure and so as to give clearance to such portions of the chute as may extend between them.

15. In centrifugal pipe casting apparatus comprising a trough or runner having a delivery 10 spout at its end, a relatively reciprocable centrifugal mold, a ladle for containing and delivering molten metal located above and in front of the mold and trough and an inclined chute arranged to receive the metal from the ladle and 15 deliver it to the trough, the improved construction in which the delivery end of the chute enters and is supported by the front end of the trough and the trough is provided with a forwardly extending angularly adjustable supporting structure 20 having side walls which at their upper portions are spaced apart by a greater distance than that of the side walls of the trough structure and so as to give clearance to such portions of the chute as may extend between them and in which 25 the chute is supported at its delivery end by the trough and at its receiving end by the side walls of the supporting structure.

16. In a centrifugal pipe casting apparatus comprising a rotatable mold relatively retractable 30 with regard to the trough through which molten metal is delivered to it, a trough having a delivery spout at its end through which metal is delivered to the relatively retractable mold and lining blocks located in the trough and forming 35 a channel for the molten metal, a ladle for containing and delivering molten metal located in front of and at a higher level than that of the mold and trough and a chute, the lower end of which enters the trough and abuts against the 40 lining blocks of the trough and the upper end of which is located to receive molten metal from the ladle, the improvement which consists in so constructing the trough that its front end does not extend substantially farther beneath 45 the chute than that portion of the lower end of the chute which lies in the front end of the trough, combining with the front end of the trough a forwardly extending angularly adjustable supporting structure having side walls 50 spaced apart by a greater distance than that separating the side walls and that portion of the trough structure in which the end of the chute is supported so as to afford increased clearance for such portions of the chute as may extend 55 beyond the front end of the trough proper, means for supporting and angularly adjusting the supporting structure and means supporting the upper end of the chute supported by and angularly adjustable with the trough supporting 60 structure.
